UNITED STATES PATENT OFFICE.

JAMES M. MORRIS, OF SALT LAKE CITY, UTAH.

CAR-REPLACER.

1,294,297.

Specification of Letters Patent. Patented Feb. 11, 1919.

Application filed November 27, 1918. Serial No. 264,425.

To all whom it may concern:

Be it known that I, JAMES M. MORRIS, a citizen of the United States, residing at Salt Lake City, in the county of Salt Lake 5 and State of Utah, have invented certain new and useful Improvements in Car-Replacers, of which the following is a specification, reference being had to the accompanying drawings.

10 This invention relates to certain improvements in car-replacers, and it is an object of the invention to provide a device of this general character having novel and improved means whereby the same can be applied in working position with convenience and facility.

Furthermore, it is an object of the invention to provide a novel and improved device of this character which affords means 20 to permit a rerailing of a car substantially without jolt or jar, and wherein the possibility of a car missing rerailing is substantially eliminated.

An additional object of the invention is to 25 provide a novel and improved device of this general character which rolling stock to be rerailed from either direction and either by pulling or pushing together means whereby the device is effectively held in working 30 position.

The invention consists in the details of construction and in the combination and arrangement of the several parts of my improved car-replacer whereby certain important advantages are attained and the device rendered simpler, less expensive and otherwise more convenient and advantageous for use, as will be hereinafter more fully set forth.

40 The novel features of my invention will hereinafter be definitely claimed.

In order that my invention may be the better understood, I will now proceed to describe the same with reference to the accompanying drawings, wherein:

Figure 1 is a view in top plan illustrating a pair of rerailing devices constructed in accordance with an embodiment of my invention and in applied position;

50 Fig. 2 is a view in elevation of the inner face of the inside member;

Fig. 3 is a view in elevation of the face of the outside member;

Fig. 4 is an enlarged transverse sectional view taken substantially on the line 4—4 55 of Fig. 1;

Fig. 5 is an enlarged sectional view taken on the line 5—5 of Fig. 1.

As disclosed in the accompanying drawings, R denotes the rails of a trackway with 60 which my improved devices are adapted to be employed, and as herein disclosed my invention comprises a set of two frogs, one of the frogs A constituting an inside member and the second frog B constituting an out- 65 side member.

Both of the frogs or members A and B are of substantially the same length and are of uniform lateral curvature, and when in applied position the convex sides toward 70 the rail as clearly illustrated in Fig. 1. The frogs or members A and B have their top surfaces arranged on substantially a uniform curvature.

The opposite ends of each of the frogs or 75 members A and B are provided with the laterally directed lugs or ears 1 extending in a direction away from the coacting rails R, and said lugs or ears 1 are adapted to have disposed therethrough the anchoring 80 spikes 2 so that said frogs or members A and B may be effectively maintained in working position. Each of the frogs or members A and B substantially midway thereof has extending laterally from its convex side a wing or knob 3 which engages beneath the ball of the adjacent rail so that the frog or member A or B is prevented from upsetting.

It is also preferred that the frogs or members A and B be formed of metal, and in order to lighten the weight thereof the side faces or walls of each of said members are hollowed out or recessed as indicated at 4. The inside frog or member A has each of its 95 opposite end portions of a width equal to substantially three times the width of the central portion of said frog or member and with the intermediate portions of the frog or member A laterally reduced.

The inner marginal portion of the frog or member A or that marginal portion re-

mote from the coacting rail R is defined by an upstanding flange 5 and the central portion of the tread surface of the frog or member A between the points a are downwardly inclined or sloped as at 6 toward the coacting rail R. The high point b of the inclined or sloped portion 6 is in substantially the same horizontal plane as the top of the rail R while the low point c is preferably about $1\frac{1}{2}$ inches below the top of the rail.

The central or high portion d of the outside frog or member B is preferably about $1\frac{1}{2}$ inches above the top of the adjacent rail 15 R so that the derailed wheel traveling thereupon will readily pass from said frog or member B upon the adjacent rail.

It is to be noted that the wings or knobs 3 are of such a length as to position the central portion of the frogs or members A and B in such proximity to the rails R to assure 20 the proper replacing of derailed wheels upon the rails R and also to permit the passage of rolling stock on the rails R without hindrance or obstruction being offered by the frogs or members A and B when applied.

It has also been fully demonstrated in practice that the members or frogs A and B as herein embodied are well adapted to replace 30 a number or string of trucks or cars that have been derailed without the necessity of moving or changing the positions of said members or frogs A and B.

From the foregoing description, it is 35 thought to be obvious that a car-replacer constructed in accordance with my invention is particularly well adapted for use by reason of the convenience and facility with which it may be assembled and operated, 40 and it will also be obvious that my invention is susceptible of some change and modification without departing from the principles and spirit thereof, and for this reason I do not wish to be understood as limiting myself to the precise arrangement and formation of the several parts herein shown in carrying out my invention in practice except 45 as hereinafter claimed.

I claim:

50 1. A car-replacer comprising an elongated laterally curved frog, the tread surface thereof being upwardly curved from opposite ends, the convex side of said frog being adapted to be positioned adjacent a rail, and 55 an outstanding wing arranged at the convex side of the member and substantially midway thereof for engagement below the ball of a rail, said wing being of a length to position the central portion of the frog entirely away from but in close proximity to the rail.

10 2. A car-replacer comprising an elongated laterally curved frog, the tread surface thereof being upwardly curved from oppo-

site ends, the convex side of said frog being 55 adapted to be positioned adjacent a rail, and an outstanding wing arranged at the convex side of the member and substantially midway thereof for engagement below the ball of a rail, the opposite end portions of the 70 member being provided with laterally directed wings through which holding spikes or the like are adapted to be directed.

3. A car-replacer comprising an elongated laterally curved frog, the tread surface 75 thereof being upwardly curved from opposite ends, the convex side of said frog being adapted to be positioned adjacent a rail, and an outstanding wing arranged at the convex side of the member and substantially 80 midway thereof for engagement below the ball of a rail, said wing being of a length to position the central portion of the frog entirely away from but in close proximity to the rail, the marginal portion of the tread 85 of the frog at its concave side being defined by an upstanding flange.

4. A car-replacer comprising an elongated laterally curved frog, the tread surface 90 thereof being upwardly curved from opposite ends, the convex side of said frog being adapted to be positioned adjacent a rail, and an outstanding wing arranged at the convex side of the member and substantially midway 95 thereof for engagement below the ball of a rail, said wing being of a length to position the central portion of the frog entirely away from but in close proximity to the rail, the marginal portion of the tread of the frog at 100 its concave side being defined by an upstanding flange, the central portion of the tread of the frog being downwardly sloped toward its convex side.

5. A car-replacer comprising an elongated laterally curved frog, the tread surface 105 thereof being upwardly curved from opposite ends, the convex side of said frog being adapted to be positioned adjacent a rail, and an outstanding wing arranged at the convex side of the member and substantially midway 110 thereof for engagement below the ball of a rail, said wing being of a length to position the central portion of the frog entirely away from but in close proximity to the rail, the marginal portion of the tread of the frog at its concave side being defined 115 by an upstanding flange, the central portion of the tread of the frog being downwardly sloped toward its convex side, the low point of said sloped portion terminating below the 120 top of the rail when in applied position.

6. A car-replacer comprising an elongated laterally curved frog, the tread surface thereof being upwardly curved from opposite ends, the convex side of said frog being 125 adapted to be positioned adjacent a rail, and an outstanding wing arranged at the convex side of the member and substantially

midway thereof for engagement below the ball of a rail, said wing being of a length to position the central portion of the frog entirely away from but in close proximity to the rail, the marginal portion of the tread of the frog at its concave side being defined by an unstanding flange, the central portion of the tread of the frog being downwardly sloped toward its convex side, the high point 10 of the sloped portion occupying substantially

the same plane as the top of the rail when in applied position.

In testimony whereof I hereunto affix my signature in the presence of witnesses.

JAMES M. MORRIS.
